UNITED STATES PATENT OFFICE.

FREDERICK PALMER, OF HAMPTON, VIRGINIA.

LOCKING-LATCH.

SPECIFICATION forming part of Letters Patent No. 276,623, dated May 1, 1883.

Application filed July 10, 1882. (Model.)

To all whom it may concern:

Be it known that I, FREDERICK PALMER, a citizen of the United States of America, residing at Hampton, in the county of Elizabeth 5 City and State of Virginia, have invented certain new and useful Improvements in Door-Locks, of which the following is a specification, reference being had therein to the accompanying drawings.

10 My invention relates to door-latches; and it consists in the combination of parts which will be hereinafter described, and pointed out in the claim.

In the accompanying drawings, Figure 1 represents a rear elevation with the back casing removed. Fig. 2 is a section through the lines $x\ x$ of Fig. 1. Fig. 3 is a partial central longitudinal section through the line $y\ y$ of Fig. 1. Fig. 4 is a perspective view of the bolt. 20 Fig. 5 represents a perspective view of the catch-bar which lies on top of the bolt. This bar is provided with a foot-piece.

Similar letters refer to similar parts throughout the several views.

25 A represents the front face-plate, and A' the main key-hole therein.

A² is a standard or guide for the latch-key.

A³ is a slot in the front end casing, in which the bolt works.

30 A⁴ A⁴ are screw-holes, by means of which the lock is secured to the door.

A⁵ is the top casing, A⁶ the bottom casing, and A⁷ A⁸ the rear and front ends, respectively.

35 A⁹ A⁹ are posts riveted to casing A, and aiding to support the top and bottom casing.

B represents the bolt proper.

B' is a narrow strip riveted to the inner side of the bolt. The key straddles this strip in 40 moving the bolt forward to the position indicated by dotted bolt lines in Fig. 1, and also in returning the bolt from the dotted lines to its normal position, as shown in the full lines in said figure.

45 B² is an ear on the end of the bar, which is rigidly secured to the rear inner side of the bolt. B³ is also an ear formed on the bolt.

B⁴ indicates the rear end of the bolt; B⁵, a slot therein.

50 B⁶ is a longitudinal slot through the body of the bolt.

B⁷ B⁸ are two slots formed in top of the bolt.

B⁹ is a slot or depression on the under side of the bolt. When the bolt is in its normal position (and not secured by the dead-latch, 55 hereinafter referred to) and the key turned forward, the lugs on said key, by engaging the sides of this under depression, will move the bolt forward and back at pleasure.

B¹⁰ represents by dotted lines the extended 60 position of the bolt when locked by the key.

C represents the inside knob, and C' the outside.

D is a bar uniting the knobs, and D' the shoulder on said bar. This shoulder fits in the 65 slot B⁶ of the bolt.

E is an arm formed on shoulder D'. By turning back the knob the bar D and shoulder D' are revolved backward, and the arm E thereby raised upward and backward, causing the 70 same to engage the ear B³ (shown in dotted lines, Fig. 1) and force the bolt back and disengage the same from its keeper. The spring hereinafter described will force the bolt forward after the hand is released from the knob. 75

F is a bar immediately above the bolt. It is provided with a ring, F', on its rear end, which encircles a post, F''.

F² is a catch on the forward end of the bar. This catch, when the bolt is unlocked, rests in 80 the forward slot, B⁸, permitting the bar to move back and forth to the extent of the length of said slot. When the bolt is turned forward by the key, (locked,) the catch F² engages the back slot, B⁷, in which position it must remain 85 until released by raising the foot F⁴, which is rigidly formed on the bottom of the bar F. (Shown in Fig. 5 and in dotted lines of Fig. 1.)

G indicates the dead-latch, and G' a vertical slot therein that works on the post G². 90

G³ is a spiral spring encircling the post. The forward end of this spring rests against the dead-latch G, and the rear end thereof rests against the back plate. By the aid of this spring the dead-latch will remain in any position placed. 95

G⁴ is a thumb-knob on the face-plate A. It is fixed to the end of post G⁵.

G⁶ is a slot (shown in dotted lines, Fig. 1) in plate A.

G⁷ represents the right-angled projection of the dead-latch, and G⁸ the slot in said latch for the reception of the latch-key. The strong lines, Fig. 1, represent the latch resting on the

bottom of plate A⁶. While in that position the bolt can be freely moved back and forth by the knobs C C'; but by raising said latch so that the projection G⁷ thereof shall engage the ear B² of the bolt said bolt is thereby secured and cannot be moved by the bar D, to which the knobs are attached. When the bolt is thus engaged the latch can be lowered by either one of two ways. A person on the inside can disengage the same by pressing down on the thumb-knob G⁴, or a person on the outside provided with a latch-key can also disengage the latch by inserting his key, thereby forcing the projection G⁷ below the ear B². The bolt can then be moved by the knob.

The remaining letters on the drawings indicate the following parts:

H is a longitudinal rib fixed to the back of face-plate A. The slot B⁵ in the rear end of the bolt straddles this rib, and is adapted to slide thereon.

I is the arm of a coiled spring, fixed to a post, I'. I² is the arm of another coiled spring, which is fixed to a post, I³. The posts I' I³ are fixed to the inside of the face-plate A.

J represents the back plate.

K is the shank of the main key, and K' K² the bits thereof. This main key, which works from the inside, can move the bolt irrespective of the position of the latch—that is to say, if the projection G⁷ of the latch be engaged with the ear B² of the bolt, such engagement only prevents the arms of lug E from forcing back the lug B³ on the bolt through the medium of the knobs, bar, and shoulders. The function of the main key is to throw the bolt forward to the position indicated by dotted lines. Such position would move the shoulder of lug B³ forward of the arm E, so that said arm could obtain no purchase on said shoulder should an attempt be made to raise the same by the knob—that is to say, when the bolt is locked (thrown forward by the key to the dotted lines) the arm E would be powerless to operate on said bolt, by reason of the fact that the smooth under side of the lug B³ would rest immediately over the top engaging projection of the arm. It must therefore be apparent that the arm E can only engage and act upon the shoulder B³ when the bolt is in its normal position indicated by the full lines in Fig. 1.

The operation of locking the bolt and securing it in the dotted position is as follows: Place the key in the hole A' and move the same forward. The lug K' of the key will raise the foot F⁴ of the bar F. This action will raise and disengage the catch F² from the slot B⁸. The lug K² of the key will at the same time engage the sides of the slot B⁹ of the bolt and force said bolt forward. The key-lugs, after having completed their half-revolution, will be turned downward, and thus permit the foot F⁴ to be lowered to its normal position, as shown in dotted lines. The key-lugs are of sufficient length to force the bolt forward, so that catch F² will engage the slot B⁷ of the bolt after the key has completed its revolution. The arm I of the spring will force the catch F² into slot B⁷ when the bolt is thrown forward by the key. When the bolt is thus locked it will be seen that by revolving the key backward in the lock the foot F⁴ and catch F² will be forced up and the bolt thrown back and the catch F² again placed in slot B⁹, thereby leaving the bar D and arm E in a position to engage and move shoulder B³ on the bolt by turning the knobs C C'. The arm I² of the back spring rests against the rear end of the bolt and presses the same forward after the same has been forced back by the knobs and its connecting means.

It must be apparent from the foregoing that this lock answers the three following purposes: a day-latch, a night-lock, and a dead-latch.

Having thus described my invention and set forth its advantages, I claim as new and desire to secure by Letters Patent—

The dead-latch G, having projection G⁷, adapted to engage and secure the lug B² on bolt B, said latch being provided with slots G⁸ G⁹, and held in position by spring G³ on post G², the thumb-knob G⁴, and post G⁵, the latter adapted to work in slot G⁶ of plate A, substantially as described and specified.

In testimony whereof I affix my signature in presence of two witnesses.

FREDERICK PALMER.
